RIVETING CLAMP

John H. Hutchings, Los Angeles, Calif., assignor,
by mesne assignments, to The Cleveland
Pneumatic Tool Company, Cleveland, Ohio, a
corporation of Ohio

Application August 7, 1939, Serial No. 288,811

13 Claims.

(CL 85—5)

This invention relates to riveting and more particularly to a centering and locking device for riveted parts.

An object of the invention is to provide a simple, practical and inexpensive device of the character described.

Another object is to provide a spring clamp that will hold riveting plates together when in alignment for the riveting operation.

A further object is to provide a riveting clamp for centering the riveting holes which may be operated by hand and readily retracted for successive use.

Other objects and advantages will appear and be brought out more fully in the following specification, reference being had to the accompanying drawing, wherein:

Fig. 1 is a perspective view showing two plates to be riveted together using the invention;

Fig. 2 is a perspective view of the riveting clamp of the invention;

Fig. 3 is a sectional view taken substantially along the line 3—3 of Fig. 1;

Fig. 4 is a view substantially similar to Fig. 3 showing the device in normal inoperative position;

Fig. 5 is an end view as seen substantially from the point 5 in Fig. 3; and

Fig. 6 is a separate view of the plunger element.

Referring more particularly to the drawing, I show a cylinder or body 10 having an end face 11, a flange 12, a tapered bore 13, and a cylindrical bore 14 having a shoulder 15. A plunger 16 is reciprocable in bore 14 and is urged outwardly by spring 17 between it and shoulder 15. A pair of jaw members 18 are pivoted at 19 to plunger 16 and have side portions 20 tapered similar to the taper of bore 13. Members 20 each have an enlarged pointed end portion 21 and a shoulder 22 thereon. A compression spring 23 is secured between members 18 in any suitable manner such as by recesses 24, and normally urges the members 18 apart. Face 11 may be knurled if desired to prevent slipping.

The operation of the device should be apparent from the foregoing description. In Fig. 1 is shown a pair of plates 25 having overlapping edge portions 26 which are to be riveted together, the plates being provided with apertures or rivet holes 27. The plates 25 are brought into approximate alignment for riveting and riveting clamps of this invention are inserted in rivet holes 27 at intervals such as one out of every four or five.

The cylinder 10 is held between two fingers as shown in Fig. 2 and plunger 16 pressed inwardly, which causes the ends 21 to be brought together as shown in dotted lines in Fig. 3 by the action of tapers 20 in tapered bore 13. Thus ends 21

can be inserted through apertures 21 and upon release of the pressure against plunger 16 and retraction of members 18, ends 21 separate through action of spring 23 as shown in Fig. 3, thus resulting in the plates 25 being clamped between face 11 and shoulders 22 while the intervening riveting holes 27 will be maintained in alignment for riveting. After the intervening riveted holes have been riveted, the clamped devices may be removed and the holes thus left can be riveted and the clamps used over and over again. Thus the riveting operation for plates can be speeded up very materially from other methods heretofore used. This time element is of great importance in certain industries, such as the manufacture of airplanes and others where speed is the important factor.

Having described my invention, what I claim is:

1. A device of the character described comprising a body having a tapered bore and a transverse end abutment, a pair of jaw members in said bore having tapered sides and shouldered end portions beyond said abutment, said end portions adapted to be moved toward each other when said members are advanced in said bore whereby said end portions may be inserted through a rivet hole, said end portions adapted to be separated to engage the under side of a plate and means to hold same against said abutment when said members are retracted in said bore.

2. A device of the character described comprising a body, an aperture in said body having a tapered portion, a plunger in said bore having an externally extending portion, a spring biasing said plunger outwardly, jaw members in said aperture secured to said plunger and each having a shouldered end portion extending beyond an end of said aperture, a face on said body adjacent said end portions, a flange on said body adjacent said plunger, whereby said end portions may be drawn together and inserted through the rivet holes of a pair of plate members when said plunger and jaw members are advanced in said aperture and said end portions may be expanded and hold said plate members against said body face, and said plunger and jaw members retracted in said aperture by the action of said spring member in engagement with said plunger.

3. A fastener for temporarily holding together at least two perforated sheets in superposed relation, including a housing having a base adapted to rest on the upper sheet, a vertical bore through said base, a retainer slidable in said housing including two legs extending through said bore, a lateral projection on each of said legs below said base, said projections being laterally movable toward each other for insertion through aligned

perforations of said sheets and laterally movable away from each other for engagement with the under side of the lower sheet, and means including a spring responsive to the slideable movement of said retainer in one direction for effecting lateral movement of said projections away from each other.

4. A fastener for temporarily holding together at least two perforated sheets in superposed relation, including a housing having a base adapted to rest on the upper sheet, a vertical bore through said base, a retaining member including two legs slideable through said bore, a lateral projection on each of said legs below said base, said projections being laterally movable toward each other for insertion through aligned perforations of said sheets and laterally movable away from each other for engagement with the under side of the lower sheet, means for laterally moving said projections toward each other during the slideable movement of said legs in one direction, and means including a spring responsive to the slideable movement of said legs in the other direction for effecting lateral movement of said projections away from each other.

5. In a device of the character described, a body having a bore extending vertically therethrough, a latch element slideable in said body through said bore, a lateral projection on said element below said body, said projection being movable into or out of the marginal edge of said bore, means active on said element normally urging it out of the marginal edge of said bore, and cam means between said body and element responsive to the slideable movement of said element in one direction for effecting movement of said projection into the marginal edge of said bore.

6. In a device of the character described, a housing having a bore extending axially therethrough, a latch element slideable in said housing through said bore, a lateral projection on said element below said housing, said projection being movable into or out of the marginal edge of said bore, means responsive to the slideable movement of said element in one direction for effecting movement of said projection into the marginal edge of said bore, and means including a spring member active on said element for effecting movement of said projection out of the marginal edge of said bore during movement of said element in the other direction.

7. A device of the character described comprising a body having a tapered bore and a transverse end abutment, a pair of jaw members slideable in said bore having shouldered end portions beyond said abutment, said end portions being movable toward each other during slideable movement of said jaw members in one direction by virtue of the engagement of said member with the tapered wall of said bore, and means active on said jaw members responsive to their slideable movement in the other direction for effecting movement of said end portions away from each other.

8. A device of the character described comprising a body having a bore extending vertically therethrough, a pair of jaw members slideable in said bore having shouldered end portions below said body, said end portions being laterally movable toward or away from each other, means between said jaw members normally urging said

end portions away from each other, and cam means between said body and jaw members responsive to the slideable movement of said members in one direction for effecting lateral movement of said end portions toward each other.

9. A temporary rivet including an elongated retaining member formed with an open end slot extending longitudinally from one end thereof, lateral projections on said member one on each side of said slot, a projecting element extending transversely of said member and slideable with respect thereto at least up to said projection, means including a spring responsive to the slideable movement of said member relative to said element in one direction for effecting lateral movement of said projections away from each other, and means responsive to the slideable movement of said member relative to said element in the other direction for effecting lateral movement of said projections toward each other.

10. A device of the character described comprising a body having a bore extending vertically therethrough, a plunger slideable in said bore, a pair of jaw members pivotally connected to said plunger for slideable movement therewith, shouldered end portions on said members below said body being pivotally movable into or out of the marginal edge of said bore, and means responsive to the slideable movement of said plunger for effecting pivotal movement of said end projections into or out of the marginal edge of said bore.

11. A device of the character described comprising a body having a bore extending vertically therethrough, a plunger slideable in said bore, a latch element pivotally connected to said plunger for slideable movement therewith, a lateral projection on said element below said body, said projection being movable into or out of the marginal edge of said bore by virtue of the pivotal movement of said element, and means responsive to the slideable movement of said latch element for effecting its pivotal movement.

12. A device of the character described comprising a body having a bore extending vertically therethrough, a plunger slideable in said bore, a pair of jaw members pivotally connected to said plunger for slideable movement therewith in said bore, shouldered end portions on said members below said body, said end portions being movable into or out of the marginal edge of said bore by virtue of the pivotal movement of said jaw members, and means responsive to the slideable movement of said jaw members for effecting said pivotal movement.

13. A device of the character described comprising a body having a bore extending vertically therethrough formed with a straight and a tapered portion, a plunger slideable in the straight portion of said bore, a pair of jaw members in the tapered portion of said bore pivotally connected to said plunger for slideable movement therewith, shouldered end portions on said members below said body, said end portions being movable into or out of the marginal edge of said bore by virtue of the pivotal movement of said jaw members, and resilient means constantly urging said members in engagement with the wall of the tapered portion of said bore whereby back and forth slideable movement of said members effects said pivotal movement.

JOHN H. HUTCHINGS.
